UNITED STATES PATENT OFFICE.

CHARLES H. COOLIDGE, OF MALDEN, MASSACHUSETTS, ASSIGNOR TO BOSTON
REFRIGERATING COMPANY, A CORPORATION OF MAINE.

COMBINED COOLING AND VENTILATING APPARATUS.

1,054,749.

Specification of Letters Patent.

Patented Mar. 4, 1913.

Application filed February 19, 1908. Serial No. 416,663.

To all whom it may concern:

Be it known that I, CHARLES H. COOLIDGE, a citizen of the United States, residing at Malden, in the county of Middlesex and 5 State of Massachusetts, have invented new and useful Improvements in a Combined Cooling and Ventilating Apparatus, of which the following is a specification.

My invention relates to improvements in 10 refrigerators and while some of its features are applicable to refrigerators in general, the particular embodiment of my invention is essentially adapted to a refrigerator made in the form of a refrigerator car.

When refrigerator cars are in transit, it is 15 often desired to ventilate them. In refrigerator cars now in use, this is accomplished by opening the trap doors in the roof of the car forming the inlets to the respective ice 20 chambers at either end thereof, whereby the air may pass through the top of the car over the goods in the cooling chamber. This mode of ventilation is not only very ineffective inasmuch as the air will simply 25 pass over the goods and have no circulation through the same, but such mode of ventilation results in cinders and smoke being carried into the cooling chamber and thereby injuring the goods.

The essential object of my invention accordingly is to effect such an arrangement 30 in the refrigerator as to form also a combined ventilating apparatus whereby air entering the car for purposes of ventilation 35 may be directed to circulate through the body of the car forming the cooling chamber and through the goods stored therein and at the same time to eliminate the possibility of any cinders or other impurities being carried into the cooling chamber; my 40 object in a word being to provide in the refrigerating apparatus means for properly ventilating the cooling chamber of the car and without possibility of injury to the 45 goods.

Another object of my invention is to provide means whereby when the trap doors are opened the shutter is automatically closed and vice versa so that the shutter cannot 50 be left open through carelessness when the car is being ventilated and on the other hand when the shutter should be open cannot through inadvertence be left closed,

Another object is to prevent sawdust and the like which may be on and around the 55 ice from choking the drain passages and thus causing the water to flow over onto the floor of the car.

Still other objects and advantages will appear hereinafter.

The invention consists in the combination and arrangement of parts set forth in the following specification and particularly pointed out in the appended claims.

Referring to the drawings: Figure 1 is a 65 vertical longitudinal sectional view of one end of a refrigerator car embodying my invention. Fig. 2 is an enlarged detail sectional view of the hinge of one of the shutters. Fig. 3 is a sectional view taken on line 70 3-3 of Fig. 1, looking toward the right. Fig. 4 is a vertical, longitudinal, sectional elevation of the end of the refrigerator car opposite to the end which is shown in Fig. 1.

Like numerals refer to like parts throughout the several views of the drawings.

In the drawings, 5 is a car body to which my invention is applied. The car body 5 at each end is preferably provided on all sides thereof with triple walls, there being suitable insulating material between the outer pair of walls and an air space between the inner pair. Within the car body 5 is an ice chamber 6 and a cooling chamber 7 which are separated by a vertical wall 8, 80 there being a passage 9 extending across the top of said wall and connecting said chambers. In the ice chamber 6 and at the bottom thereof is an ice support 10 comprising a plurality of horizontal slats or bars 11 supported at their opposite ends on supports 12. On three of the sides of the ice chamber 6 are slats or bars 13 secured to the walls of said chamber at suitable distances apart so as to prevent ice from coming in contact 90 with said walls, while on the fourth side of said chamber is a screen 14 separated from the adjacent wall by an air space so that when the ice chamber is filled with ice there are vertical passages on all sides thereof 100 which permit a free circulation of the air from the passage 9 downwardly through said chamber.

Located below the ice support 10 is a shelf 15 mounted on a suitable support 16 105 and sloping downwardly toward the middle

of the chamber, said shelf being preferably covered with a piece of sheet metal 17. The shelf 15 is separated from the outer wall of the car body by an air passage 18 through which the cold air may descend. At the lower edge of the shelf 15 I provide a trough or gutter 19 which is adapted to receive the water which flows down the surface of said shelf and the water flowing to the ends of said gutter falls onto a second shelf 20 which extends from the wall 8 downwardly toward the middle of the chamber in which it is located, said shelf being also preferably provided with a covering 21 of sheet metal. At the lower edge of the shelf 20 is a vertical wall 22 which compels the water to flow into two drain pipes 23 located at opposite ends, respectively, of the shelf 20. A screen 24 suspended from the shelf 15 by means of hooks 25 meets the shelf 20 above the inlet orifices of the pipes 23 and thus any sawdust or the like which may come from the ice onto the shelf 20 is held away from said inlet orifices and, therefore, is prevented from clogging said pipes. Below the wall 8 is located an air passage 26, while a screen 27 extends entirely across said passage. Located beneath the lower ends of the pipes 23 are traps 28 which may be of any usual or desired construction and as herein shown are pivoted at 29. Two openings 30, 30 extend through the roof 31 of the car body 5, these openings being provided for the admission of the ice into the ice chamber 6. Over the openings 30 are arranged trap doors 32 hinged at 33, said doors being adapted to swing through an arc of 180°. Located in the openings 30 below the trap doors 32 are closures 34, 34, respectively, which consist of tapered plugs made up of three walls suitably packed with insulating material and having an air space similar to the walls of the car body 5. In order to close the spaces or passages 9, I provide three shutters 35 fast to a shaft 36 extending transversely of the car body 5 and mounted to rock in suitable bearings. Fast to the shutter 35 are two arms 37 to which two rods 38 are pivotally connected, respectively, said rods extending through holes 39 transversely of and beyond the plugs 34, respectively. On the upper ends of the rods 38 are journaled rolls 40 adapted to engage plates 41 fast to the trap doors 32, respectively. When the trap doors 32 are lifted from the position shown in full lines, Fig. 1, to the position shown in dotted lines therein, the shutters 35 by gravity rock on their axis into the position shown in dotted lines, Fig. 1, the rolls 40 during this time remaining in contact with the plates 41, respectively. The shutters 35 being now closed, continued opening movement of the trap doors 32 through the remainder of an arc of 180° separates the plates 41 from the

rolls 40, respectively, and it will be evident that the shutters 35 remain closed during this latter part of the movement of said trap doors.

It will be understood that if only one of the trap doors 32 is opened the shutters 35 will remain open until the second trap door has been opened. The plugs 34 are then withdrawn upwardly from their places and laid upon the roof 31. The ice chamber can now be filled with ice and when this is done the plugs 34 are returned to their places and the trap doors 32 are closed. As the trap doors 32 close the plates 41 strike the rolls 40, respectively, and impart a downward movement to the rods 38 which results in the shutters 35 being rocked on their pivots into the position shown in full lines, Fig. 1. The car having now been iced, a circulation of air commences within the same, the air rising to the roof thereof and passing through the spaces 9 into the ice chamber 6. The cooling of the air in the ice chamber causes it to fall downwardly through the passages on all sides of the ice, through the air passage 18 and through the spaces between the bars 11 into the space below the shelf 20 and thence through the passage 26 into the cooling chamber 7.

There are many times when it is unnecessary to use ice in refrigerator cars, and at such times it often becomes desirable to ventilate the cars, especially when passing through cold tunnels. To do this the trap doors 32 are raised to the position shown in dotted lines, Fig. 1, the plugs 34 are withdrawn and as hereinbefore stated when the trap doors 32 are thus raised the shutters 35 close by gravity. Therefore, as the car is passing through a tunnel the air from the tunnel passes downwardly through the openings 30 and instead of being allowed to pass through the passages 9 which are now closed by the shutters 35, said air passes downwardly within the ice chamber 6 into the chamber therebelow, thence through the opening 26 through the entire length of the car and outwardly therefrom through similar openings and passages in a duplicate refrigerator apparatus, located in the opposite end of the car.

If it were not for the openings 9 being closed by the shutters 35 during the ventilating just described, smoke and cinders would pass from said opening into the cooling chamber 7 and would injure the fruit, vegetables or other goods stored therein. By forcing the air to pass downwardly through the ice chamber no cinders nor smoke find their way into the cooling chamber since the cinders find lodgment in the ice chamber. To prevent ice from accidentally passing from the ice chamber 6 into the cooling chamber 7 and also to prevent train hands and other persons from reaching their arms

into said cooling chamber and stealing fruit, I provide screens 42 extending across the passages 9.

Having thus described my invention, what I claim and desire by Letters Patent to secure is:

1. In a combined ventilating apparatus, a housing having a feeder passage and provided with upper and lower air passages 10 communicating with the feeder passage and the interior of the housing, one wall of the housing being provided with an opening leading to the outer atmosphere, a door pivoted to swing about a substantially horizontal axis and adapted to close said opening, a shutter pivoted to swing about a substantially horizontal axis and adapted to close said upper passage, and means interposed between said shutter and said door 20 whereby during a portion of the opening movement of said door said shutter is adapted to completely close, and whereby during the remainder of the opening movement of said door the shutter remains closed, said lower passage being open at all times.

2. In a combined ventilating apparatus, a chamber provided with upper and lower air passages and an intermediate feeder passage communicating with said first passages, 30 said upper and lower passages also communicating with the interior of the chamber, one wall of said chamber being provided with an opening leading to the atmosphere, a door hinged to close said opening, a shutter pivoted to close said upper passage, and means interposed between said door and said shutter whereby during the initial portion of the opening movement of the door said shutter is adapted to completely close, said 40 shutter being adapted to remain closed during the remaining portion of the opening movement of the door, said lower passage being open at all times.

3. In a combined ventilating apparatus, a chamber provided with upper and lower air passages and a feeder passage intermediate said first passages, said upper and lower passages communicating with the feeder passage and the interior of said chamber, one 50 wall of the chamber having an opening leading to the outer atmosphere, a door adapted to close said opening, a shutter adapted to close the upper one of said passages, and means interposed between said shutter and said door whereby during the initial portion of the opening movement of said door said shutter is adapted to completely close, and whereby during the remainder of said opening movement of said door said shutter remains closed, said lower passage being open at all times.

4. In a combined ventilating apparatus, a chamber provided with an intermediate feeder passage and upper and lower air 60 passages communicating with the feeder

passage and with the interior of the chamber, one wall of said chamber having an opening therethrough leading to the outer atmosphere, a door adapted to close said opening and arranged to be normally held closed by gravity, a shutter adapted to close said upper passage and arranged to be closed by gravity, and means interposed between said shutter and said door whereby during the initial portion of the opening movement of said door said shutter is adapted to completely close, said shutter being adapted to remain closed during the remaining portion of the opening movement of the door, said lower passage being open at all times.

5. In a combined ventilating apparatus, a chamber having a feeder passage and upper and lower passages communicating therewith and with the interior of the chamber, one wall of the chamber having an opening leading to the atmosphere, a door adapted to close said opening, a pivoted shutter adapted to close said upper passage, and a rod arranged between the door and the shutter and adapted to be actuated by said door but disconnected therefrom, whereby said door during the final portion of its closing movement is adapted to completely open said shutter, said shutter being adapted to remain closed during the initial portion of the closing movement of the door, said lower passage being open at all times.

6. In a combined ventilating apparatus, 100 a chamber provided with a main passage and upper and lower passages communicating with the main passage and with the interior of the chamber, said chamber also having in one wall an opening a closure for said opening, a door also adapted to close said opening, a shutter adapted to close said upper passage, and means interposed between said shutter and said door and extending transversely of and past said closure whereby during the final portion of the closing movement of said door said shutter is adapted to completely open, said shutter remaining closed during the initial portion of the closing movement of the door, said 110 lower passage being open at all times.

7. In a combined ventilating apparatus, a chamber provided with a main passage and an air passage communicating therewith and with the interior of the chamber, one wall of said chamber being provided with an opening, a door adapted to close said opening, a shutter normally closing said passage, and means interposed between said shutter and said door and extending transversely of and past said closure whereby during the final portion only of the closing movement of said door said shutter is adapted to completely open.

8. In a combined ventilating apparatus, 120

- 2 a main chamber having an air passage and an opening, said air passage communicating with the main chamber, a door adapted to close said opening, a pivoted shutter normally closing said passage, an arm carried by the shutter and a rod interposed between said arm and said door whereby during the final portion of the closing movement of said door said shutter is completely opened.
- 10 9. A combined ventilating apparatus having a chamber provided with a feeder passage and an air passage opening into said feeder passage and into said chamber, one wall of the chamber having an opening, a pivoted door adapted to close said opening, a normally closed shutter for said passage, a rod connected to said shutter, and a roller journaled on said rod and adapted to engage said door whereby said door during the final portion of its closing movement is adapted to completely open said shutter.
- 15 10. In a combined ventilating apparatus, a chamber provided with two main passages therethrough and air passages communicating with the main passages and with the chamber, one wall of said chamber being provided with two openings, a pair of doors adapted to close said openings, shutters adapted to close said air passages, and means interposed between said doors and said shutters whereby during the final closing movement of either of said doors the corresponding shutter is adapted to completely open, and whereby during the remainder of said closing movement said shutters remain stationary.
- 20 11. In a combined ventilating apparatus, a housing provided with a wall dividing the housing into an inner chamber and a main passage, said wall having an upper passage and a lower passage connecting the inner chamber with said main passage, said housing having a roof provided with an opening leading from the outside thereof into the main passage, a shutter adapted to close said upper passage, a door adapted to close said opening in the roof, and means interposed between said shutter and said door whereby during the initial portion of the opening movement of said door said shutter is adapted to completely close, said shutter being adapted to remain at rest during the remaining portion of the opening movement of said door, said lower passage being open at all times.
- 25 12. A combined ventilating apparatus comprising a housing having an inner compartment and end main passages, said housing having upper and lower passages at the ends of the inner compartment communicating the inner compartment with said main passages whereby air may be circulated through said passages and through the inner compartment, said housing further having inlets at its ends communicating with the main passages, and means for controlling the upper passage at one end of the housing whereby air entering said main passage through the adjacent inlet thereto may be directed to pass through said passage into its lower end passage and through said inner compartment and the opposite lower passage, and thence through said main passage at the opposite end of the housing, said upper passage being adapted to be completely closed when said inlet is open whereby air is not permitted to pass therethrough.
- 30 13. In a combined ventilating apparatus, a housing provided with a wall dividing the housing into an inner chamber and a main passage, said wall having an upper passage and a lower passage connecting the inner chamber with said main passage, said housing having a roof provided with an opening leading from the outside thereof into said main passage, a door for said opening, a normally closed shutter for said upper passage, an arm fast to said shutter, and a rod pivotally connected to said arm and adapted for engagement with said door whereby said door during the final portion of its closing movement is adapted to open said shutter, said lower passage being open at all times.
- 35 14. A combined ventilating apparatus comprising a housing having an inner compartment and end main passages, said housing having upper and lower passages at the ends of the inner compartment communicating the inner compartment with said main passages whereby air may be circulated through said passages and through the inner compartment, said housing further having inlets at its ends communicating with the main passages, and means for controlling the upper passage at one end of the housing whereby air entering said main passage through the adjacent inlet thereto may be directed to pass through said passage into its lower end passage and through said inner compartment and the opposite lower passage, and thence through said main passage at the opposite end of the housing, said upper passage being adapted to be completely closed when said inlet is open whereby air is not permitted to pass therethrough.
- 40 15. A combined ventilating apparatus comprising a housing provided with partitions near its ends, said housing also having openings at its ends leading from the atmosphere into the spaces between said partitions and the ends of the housing, doors adapted to close said openings, said partitions having upper and lower passages communicating the interior of the housing with the spaces at the ends thereof, shutters for the upper passages in the partitions, and operating means connected between said shutters and said doors whereby during the initial portion of the opening movement of said

either of the doors the corresponding shutter is adapted to completely close and remain closed during the remaining portion of the opening movement of the door, and whereby upon the final portion of the closing movement of either of said doors the corresponding shutter is completely opened, the shutters remaining at rest during the initial portion of the closing movement of

the corresponding door, the lower passages 16 in said partitions being open at all times.

In testimony whereof I have hereunto set my hand in presence of two subscribing witnesses.
